Floyd J. McMichael, Orlando, Fla.

Application February 8, 1945, Serial No. 576,739

10 Claims. (Cl. 62—19)

1

This invention relates to an improved refrigerator car but, however, is also adaptable to ice boxes, ice chests and other refrigerating units such as are used by butchers and the like.

Refrigeration of the lading of refrigerator cars is dependent upon the circulation of air within the car. When ice is used as a refrigerating medium, it is placed in bunkers at the ends of the car. This causes a natural circulation of air because air that is in contact with the ice, as it becomes chilled, becomes more heavy than the warmer air and flows downwardly toward the floor of the car. As the cold air passes downward, it will force the warmer air toward the ceiling. The warmer air will then flow along the ceiling toward the bunkers at the ends of the car to replace the air which has left the bunkers from the bottom. This warm air will press downward as it in turn becomes chilled by the ice, thereby setting up the natural air circulation within the car. When the bunkers are filled so that the ice is near the ceiling of the car, the entire air content of the car will be in motion. But as the ice melts and recedes in the bunkers, the moving air will only be as high as the remaining ice in the bunkers. This causes a stratum of dead or non-circulating air between the ceiling of the car and the stratum of moving air. As the ice in the bunkers recedes further, the stratum of non-circulating air becomes greater with the result that the lading at the top of the load does not receive sufficient refrigeration.

It is accordingly obvious that the height of the circulating air in the car, and consequently the effectiveness of the refrigeration of the contents of the car, is largely determined by the presence or absence of ice at the upper end portions of the bunkers. It is for this reason that the bunkers are initially filled full of ice while, also, the car is reiced during transit.

The usual bunkers of a refrigerator car each hold, when full, something over five thousand pounds of ice. The advantage of using such a large quantity of ice lies in the fact that the circulating stratum of air will be maintained high in the car a correspondingly long period of time while, also, the necessity for frequently reicing the car in transit is avoided. The disadvantage of the practice lies in the fact that when the car reaches destination and is emptied, the large quantity of ice remaining in the bunkers becomes a loss.

To overcome the disadvantage just noted, so-called stage icing has gained some favor. As practiced, the bunkers of the car are provided

with adjustable bottom racks which may be fixed at different elevations in the bunkers. Accordingly, when such a rack is adjusted, say, to a middle position, for instance, in a bunker, only the upper half of the bunker will contain ice when the bunker is full. The advantage of the expedient resides in a resultant economy of ice while also, the column of ice is supported at the upper portion of the car in order to maintain the stratum of circulating air as high as possible, as previously noted. The disadvantage of the expedient resides in the fact that the small quantity of ice does not refrigerate the contents of the car efficiently while, moreover, it is necessary to frequently reice the car in transit.

It is accordingly an object of the present invention to provide a refrigerator car which will possess the advantages but not be subject to the disadvantages noted.

20 A further object of the invention is to provide a car wherein the ice bunkers may initially be either partially or wholly filled with ice, as may be desired, so that a saving in the quantity of ice used may thus be effected if so chosen, and 25 wherein, as the ice melts, any ice remaining in the bunkers will always be maintained at the upper end portions of the bunkers to thus serve to chill the warm air collecting at the top of the car and maintain the effective refrigeration of 30 the contents of the car.

Another object of the invention is to provide a car wherein each of the ice bunkers thereof will embody a bottom rack movable up and down in the bunker, and wherein means will be provided 35 for progressively maintaining said rack at any given height in the bunker in response to a corresponding weight of ice on the rack so that, as the bunker is filled, said rack will sink to the lower portion of the bunker, while, as the ice 40 melts, the rack will be caused to rise for maintaining the remaining ice in the bunker at the upper portion thereof.

Still another object of the invention is to provide a car wherein springs of graduated strength 45 will be employed to variably support the bottom racks of the bunkers, and wherein, as the bunkers are filled with ice, said springs will be compressed as the racks descend under the weight of added 50 ice thereon, while, as the ice melts, the springs will expand to lift said racks.

And a still further object of the invention is to provide a car wherein indicators visible externally of the car will be provided for indicating 55 the level of the bottom racks of the bunkers so

that an attendant may readily determine how much ice remains in the bunkers.

Other and incidental objects of the invention will appear during the course of the following description, and in the drawings:

Figure 1 is a diagrammatic side elevation of a refrigerator car broken away to disclose the ice bunkers at the ends of the car, this view showing the bunkers choked with ice.

Figure 2 is a fragmentary diagrammatic elevation of one end of the car broken away and showing the ice bunker disclosed approximately half full of ice.

Figure 3 is a view similar to Figure 2 and showing the ice bunker approximately one-quarter full of ice.

Figure 4 is a fragmentary vertical, longitudinal section through the car body at one of the bunkers.

Figure 5 is a horizontal section through the bunker of Figure 4.

Figure 6 is a plan view of the bottom rack employed.

Figure 7 is a vertical, longitudinal section through said rack.

Figure 8 is a fragmentary, transverse vertical section through the car body at the upper end of the bunker of Figure 4.

Figure 9 is a detail section through one of the housing tubes for the lifting springs employed.

Figure 10 is a detail section through the forward end of said tube.

Figure 11 is a detail section through the rear end of said tube.

Figure 12 is a detail elevation of one set of the lifting springs.

Figure 13 is a detail elevation showing the springs nested.

Figure 14 is an elevation of one end of the car partly broken away to show the indicator cable.

Figure 15 is a detail section particularly showing the bottom pulley for the indicator cable.

Figure 16 is a detail elevation of said bottom pulley.

Figure 17 is a detail elevation of a modified arrangement of lifting springs wherein said springs are disposed end to end.

Figure 18 is a fragmentary vertical, longitudinal section through one end of a car embodying a further modification of the invention wherein counterweights are employed.

Figure 19 is an end elevation partly broken away of the modification shown in Figure 18.

Figure 20 is a detail section showing a set of counterweights.

Referring now more particularly to the drawings, I have shown a refrigerator car embodying a body 7 in which is disposed the usual floor grating 8 spaced above the floor of the body. Extending transversely of the body near the ends thereof are baffles 9 defining ice bunkers 10 and 11 respectively. At the lower ends of the bunkers are bumpers 12 on a level with the grating 8, and hinged to the roof of the car at the upper ends of the bunkers are the usual doors 13 so that the bunkers may be conveniently filled with ice. The customary props for holding the doors partially open, when so desired, are indicated at 14. Conventional drains 15 are provided for the bunkers, and these drains are equipped with the usual traps to prevent the escape of the cold air within the car downwardly through the drain pipes.

As will be observed, the baffles 9 terminate short of the ceiling of the car body to provide

air inlet passages 16, and also terminate short of the grating 8 and bumpers 12 to provide air outlet passages 17. Overlying said passages are grilles 18. Thus, warm air collecting near the ceiling of the car may circulate over the baffles through the passages 16 to contact the ice in the bunkers and become chilled by the ice, whence the chilled air may circulate downwardly through the bunkers to emerge beneath the baffles 10 through the passages 17 above the grating 8, or spread lengthwise of the car beneath said grating to emerge upwardly throughout the length of the car between the bunkers. As the bunkers 10 and 11 are identical, a further description in connection with one of said bunkers will suffice for both, the bunker 10 being chosen. However, the same reference numerals are applied to corresponding parts of both.

Referring now to the bunker 10, I provide, as particularly seen in Figures 4 and 5 of the drawings, a corrugated sheet metal lining 19 which is bolted in place or otherwise suitably fixed within the bunker and serves to protect the walls thereof from injury by ice placed in the bunker. This lining also serves to provide tracks 20 at the sides of the bunker, like tracks 21 at the ends of the bunker, and a pair of like adjacent tracks 22 at the outer side of the bunker medially thereof. All of these tracks extend vertically from top to bottom of the lining. Between the tracks 22, one end margin of the lining is bent to form a vertically extending channel 23 while the other end margin of said lining is bent to form a vertical lip 24 which extends parallel to the adjacent side wall of the channel to define a vertical slot 25.

Freely movable up and down in the bunker 10 is a bottom rack 26 which is preferably provided with a slat bottom so that air may circulate therethrough while, also, water may readily drain through the rack. Fixed to the sides of the rack are rollers 27 which travel against the tracks 20 of the lining 19, and fixed to the ends of the rack are rollers 28 which travel against the tracks 21. Rising from the ends of the rack, as particularly seen in Figure 7, are posts 29, and fixed to said posts are rollers 30 which align with the rollers 28 and travel against the tracks 21 to prevent the rack from teetering longitudinally under the weight of an uneven load of ice thereon. However, care should be taken, when filling the bunker with ice, to load the rack more or less evenly.

Formed in the outer side of the rack 26 medially thereof is a notch 31 which, as seen in Figure 15, faces the channel 23 of the lining 19, and fixed to the rack are rollers 32 which straddle said channel and travel against the tracks 22 of said lining. The rollers 27, 28, 30 and 32 will thus guide the rack for free vertical movement, and projecting from the outer side of the rack at the notch 31 freely into the slot 25 of the lining is an arm 33.

Mounted against the ceiling of the car body 7 at the side walls of the body are housing tubes 34. As particularly seen in Figures 4 and 9 of the drawings, these tubes are provided with base plates 35 which extend over the bunker 10, and mounted against the forward end portions of said plates are pairs of spaced pulleys 36 aligning with the tubes. The base plates as well as said pulleys are securely fastened by bolts or other suitable fastening devices extending through the roof of the car, and closing the ends of said tubes, as seen in Figure 11, are removable

plugs 37 and 38 respectively. If so desired, the plug 37 may be eliminated and the tubes formed with integral end walls in lieu thereof.

Removably disposed in each of the tubes 34 is a set 39 of lifting springs for the bottom rack 26. As shown in detail in Figure 12 of the drawings, each set includes a spring 40 which is the strongest of the set, a somewhat longer and weaker spring 41, a spring 42 which is somewhat longer and weaker than the spring 41, a spring 43 which is somewhat longer and weaker than the spring 42, a spring 44 which is somewhat longer and weaker than the spring 43, and a spring 45 which is the weakest and longest of the set. The springs are thus of graduated length as well as graduated strength. Furthermore, said springs are, as brought out in Figure 13, of graduated diameter so that said springs may be nested, and while I have shown the use of six springs in a set still, as will be understood, the number may be varied, as found most expedient.

Suitably connected to the rack 26 near the corners thereof are cables or other suitable flexible elements 46 which extend over the pulleys 36 freely through the plugs 37 of the housing tubes 34 and through the nested sets 39 of the lifting springs in said tubes, and fixed on the free ends of said cables are abutment plates 47. The rack is thus operably connected with said sets of springs and, as brought out in Figure 10, all of the springs of each set abut a corresponding one of the end plugs 37. Furthermore, it is to be noted that the several springs of each set are so proportioned in length that the sets of springs may be compressed to accommodate the vertical throw of the rack 26.

Assuming now that the bunker 10 is being filled with ice, it will be seen, as shown in Figure 3, that when the bunker is say approximately one-quarter full of ice, the sets 39 of lifting springs for the rack 26 will be compressed by the weight of the ice on the rack, about one-quarter of the compression movement of said sets of springs and will support at the upper portion of the bunker the small volume of ice represented. In other words, the cubical volume of the bunker above the rack at any given level of said rack is so much, the quantity of cracked ice required to fill said volume will weight so much, and the graduated springs of the sets 39 are of chosen strength such that when the sets of springs are compressed a proportionate fraction as the rack drops and said rack reaches said level, the sets of springs will counterbalance the rack with the load of ice thereon and support the rack stationary. It will thus be seen that when the bunker 10 is being filled and the load of more and more ice is added on the rack 26, said rack will drop a corresponding distance in the bunker so that the bunker may accommodate the ice added. Figure 1 of the drawings shows both of the bunkers 10 and 11 choked with ice, while Figure 2 shows the bunker 10 approximately half full of ice.

In this connection, it is to be observed that when the bunker 10 is originally serviced with ice, said bunker will, most usually, in accordance with customary practice, be choked with ice clear to the roof of the car body, as shown in Figure 1 of the drawings. Accordingly, the maximum resistance of the sets 39 of the lifting springs to the downward movement of the rack 26 will be overcome so that the rack will rest on the bumpers 12. The rack will then remain in this bottom position until enough ice has melted to lessen

the load on the rack sufficiently when, as will be appreciated in view of the foregoing, the rack together with the remaining ice thereon will be lifted a corresponding distance in the bunker.

As will be understood, it is necessary to normally provide free space in the bunker 10 between the upper surface of the ice in the bunker and the ceiling of the car body so that the bunker may be replenished with ice at any time desired. Accordingly, the sets 39 of the lifting springs are of such graduated strength and are so disposed that said springs will lift the rack and any ice remaining thereon only until the upper surface of the ice remaining in the bunker reaches a predetermined normal level near the ceiling of the car body, say at a level about half way of the air inlet passage 16, as shown in Figures 2 and 3 of the drawings. In such instance, ample free space will remain above the ice in the bunker so that more ice may be added, as found expedient.

It will thus be seen that when the bunker 10 is initially choked with ice, as shown in Figure 1, the quantity of ice in the bunker above the normal level of ice therein represents excess weight on the rack 26 so that the rack will not begin to rise under the action of the sets 39 of lifting springs until sufficient ice has melted to reduce the load on the rack to something less than the load represented by the quantity of ice required to fill the bunker up to the normal level of ice therein. Of course, the foregoing condition will be presented only while the bunker is choked with ice, and when the ice melts and the load reaches sufficiently reduced weight, the sets 39 of lifting springs will then respond so that as still more and more ice melts, the rack will, as previously stated, be lifted a corresponding distance in the bunker. Settling of the ice in the bunker, as the ice melts, will accordingly be continuously compensated for by the rise of the rack so that the upper surface of the ice remaining in the bunker will be maintained at or near the chosen predetermined normal level of ice in the bunker near the ceiling of the car body. Thus, assuming approximately half of the ice to be melted, as shown in Figure 2, the rack 26 will return to substantially the mid-position indicated, while when approximately three-fourths of the ice has melted, the rack will return to substantially the position shown in Figure 3. I accordingly provide an arrangement wherein the bunkers may be initially choked with ice or, should it be desired to economize ice, filled only partially full with any quantity of ice desired while the ice present in the bunkers will always be maintained at the upper end portions of the bunkers to chill the warm air collecting at the ceiling of the car and so maintain the effective refrigeration of the contents of the car.

Since, in accordance with the invention, the upper surface of any ice remaining in the bunkers will be maintained high up in said bunkers so that it will be impossible to estimate how much ice remains if the bunkers are inspected from the top, I provide indicators visible externally of the car, one of said indicators being shown in connection with the bunker 10.

Fixed to the adjacent end wall of the car body, as particularly seen in Figures 4 and 15 of the drawings, is a stub shaft 48, and mounted on said shaft is a pulley 49 disposed at the lower end of the channel 23 of the lining 19. Mounted adjacent the roof of the car is a suitable indicator mechanism indicated as a whole at 50. The de-

tails of said mechanism are unimportant except to note that said mechanism includes a pulley 51 operable to rotate a shaft 52 upon which is mounted, as seen in Figure 14, a needle 53. Trained about the pulleys 49 and 51 is a cable 54 one reach of which is accommodated in the channel 23 of said lining. The other reach of said cable is accommodated by the slot 25 and, as shown in Figure 16 of the drawings, extends through the free end of the arm 33 of the rack 26. Connecting said arm with the cable are knobs 55 disposed above and below the arm. Thus, as the rack rises and falls, the indicator needle 53 will, as will be understood, be swung to indicate the quantity of ice in the bunker.

In Figure 17 of the drawings, I have shown a slight modification wherein the sets of lifting springs are each composed of a number of springs 56 disposed end to end instead of being nested as in the preferred embodiment of the invention. The springs 56 correspond in every way to the springs of the sets 39 of springs and need no further description.

In Figures 18, 19 and 20 of the drawings, I have shown a further modification of the invention wherein counterweights are employed in lieu of the lifting springs disclosed in the preferred embodiment of the invention.

The car body is indicated at 57, one of the ice bunkers therein at 58, the movable bottom rack of the bunker at 59, pulleys at 60, and at 61 the cables or other suitable flexible elements which are trained over said pulleys and connected to the ends of the rack, all of these parts being identical with corresponding parts first described.

In accordance with this variation of the invention, extra pulleys 62 for the cables 61 are provided, and suitably secured to the floor of the car body below said pulleys are vertically disposed housing tubes 63. Fitting in each of said tubes is a set of sleeves 64 abutting end to end and of graduated internal diameter to define a series of vertically spaced, horizontally stepped shelves 65.

The sleeves 64 may be removably fitted in the tubes 63 if so desired, and housed in each of said tubes is a set of counterweights which, for convenience of description, are indicated at 66, 67, 68, 69, 70, and 71. In the present instance, I have shown the use of six counterweights in a set but, of course, the number may be varied.

The free end portions of the cables 61 extend freely through the counterweights 67, 68, 69, 70, and 71 of the respective sets and are fixed to the counterweights 66. All of the counterweights are thus operably connected with the cables and, as will be observed, the counterweights of each set are of graduated diameter so that, with the exception of the counterweights 66, said counterweights normally rest in vertical spaced relation upon the shelves 65. Also, the counterweights of each set are of graduated weight, the counterweight 66 being the lightest in weight and the counterweight 71 the heaviest.

Assuming now that the bunker 58 is empty, it will be seen that the several counterweights above the counterweight 66 will rest upon the shelves 65 of the sleeves 64 while the counterweights 66 will sustain the rack at the upper end portion of the bunker. Accordingly, as the bunker is filled with ice and the rack descends under the load thereon, the counterweights 66 will be caused to rise and pick up the counterweights 67, then the counterweights 68, and so on until the counterweights 71 are picked up and the rack rests at the bottom of the bunker. As the ice in the bunker melts

and the counterweights move down to elevate the rack in response to the diminishing load thereon, the counterweights will return to normal position in reverse order. As will be appreciated, the counterweights 71 will first come to rest, then the counterweights 70, and so on until the rack is returned to its original position. Thus, as will be perceived, the counterweights will function to maintain any ice remaining in the bunker at the upper portion thereof so that the upper surface of the ice will be maintained at or near a predetermined normal level near the ceiling of the car body. Effective refrigeration will thus be maintained.

15 Except as noted, the modification last described is otherwise identical with the preferred embodiment of the invention, and further explanation is accordingly unnecessary.

Having thus described my invention, what I claim is:

20 1. A refrigerating unit including a body having an ice bunker therein, a rack movable up and down in the bunker and adapted to support ice thereon, and graduated counterbalancing means connected with the rack and operable in response to variation in the weight of a load of ice on the rack to counterbalance the rack at a corresponding level in said bunker and maintain the upper surface of said load near a predetermined normal level at the upper portion of the bunker.

25 2. A refrigerating unit including a body having an ice bunker therein, a rack movable up and down in the bunker and adapted to support ice thereon, and graduated yieldable lifting means connected with the rack and operable to

30 increasingly oppose the lowering of the rack as the rack shifts downwardly in said bunker for sustaining the rack at progressed levels selectively and maintaining the upper surface of a load of ice on the rack near a predetermined normal level at the upper portion of the bunker.

35 3. A refrigerating unit including a body having an ice bunker therein, a rack movable up and down in the bunker and adapted to support ice thereon, and graduated lifting means connected with the rack and operable as the ice melts to raise the rack in said bunker a distance sufficient to compensate for the loss of bulk of the ice and maintain the upper surface of the ice near a predetermined normal level at the upper portion of the bunker.

40 4. A refrigerating unit including a container, a rack movable up and down in the container and adapted to support ice thereon, and lifting means associated with the rack and including elements of graduated lifting capacity, said means being responsive to variation in the weight of a load of ice on the rack for sustaining the rack at progressed levels selectively and maintaining the upper surface of the ice near a predetermined normal level at the upper portion of the container.

45 5. A refrigerating unit including a body having an ice bunker therein, a rack movable up and down in the bunker and adapted to support ice thereon, graduated counter balancing means operable to sustain said rack at progressed levels selectively and maintain the upper surface of a load of ice on the rack near a predetermined normal level at the upper portion of the bunker, and an indicator connected with the rack for operation thereby to indicate the elevation of the rack in said bunker.

50 6. A refrigerating unit including a body having an ice bunker therein, a rack movable up and

down in the bunker and adapted to support ice thereon, and springs of graduated strength associated with the rack and operable to sustain the rack at progressed levels selectively and maintain the upper surface of a load of ice on the rack near a predetermined normal level at the upper portion of the bunker.

7. A refrigerating unit including a body having an ice bunker therein, a rack movable up and down in the bunker and adapted to support ice thereon, housing tubes fixed within the body, springs of graduated strength disposed within said tubes, and flexible elements forming an operative connection between the rack and said springs, the springs being operable to sustain the rack at progressed levels selectively and maintain the upper surface of the ice near a predetermined normal level at the upper portion of the bunker.

8. A refrigerating unit including a body having an ice bunker therein, a lining within the bunker and forming tracks, a rack movable up and down in the bunker and adapted to support ice thereon, rollers carried by the rack and engaging said tracks for guiding the rack in its up and down movement, housing tubes fixed within the body above the bunker, springs of graduated strength disposed in said tubes, and flexible elements forming an operative connection between the rack and said springs, the springs being operable to sustain the rack at progressed levels selectively and maintain the upper surface of the ice near a predetermined normal level at the upper portion of the bunker.

9. A refrigerating unit including a body having an ice bunker therein, a rack movable up and down in the bunker and adapted to support ice thereon, a set of counterbalancing weights for the rack, means normally supporting said weights in vertical spaced relation, and means operable by the rack as it descends in said bunker to pick up said weights in sequence, said weights being of graduated heaviness increasing from bottom to top of the set.
10. A refrigerating unit including a body having an ice bunker therein, a rack movable up and down in the bunker and adapted to support ice thereon, housing tubes mounted within the body adjacent the bunker, sleeves disposed in said tubes and of graduated diameter to define stepped vertically spaced shelves, counterweights for the rack normally resting on said shelves, and means operable by the rack as it descends in said bunker to pick up said weights in sequence.
